UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

BUTTONHOLE-SEWING MACHINE.

1,233,270.

Specification of Letters Patent. Patented July 10, 1917.

Application filed October 28, 1915. Serial No. 58,429.

To all whom it may concern:

Be it known that I, GEORGE S. HILL, a citizen of the United States, residing at Strafford, in the county of Strafford and 5 State of New Hampshire, have invented certain new and useful Improvements in Buttonhole-Sewing Machines; and I do hereby declare the following to be a full, clear, and exact description of the invention, such as 10 will enable others skilled in the art to which it appertains to make and use the same.

This invention relates to that class of buttonhole sewing machines in which the stitch forming mechanism is rotated during the 15 sewing about the ends of a buttonhole.

The invention is intended primarily as an improvement in the buttonhole sewing machine shown and described in Patent No. 1,063,880, June 3, 1913, although it is not 20 confined in its application to this machine, but may be embodied with advantage in other machines.

In the machine of the above patent the stitch forming mechanism is rotated rotation after rotation in the same direction in 25 sewing about successive buttonholes, and in order to prevent the twisting together of the stay and under threads they are led to the turret on which the under thread mechanism is mounted through thread-supply guides which are rotated in unison with the 30 turret and in the opposite direction. The threads lead horizontally from the thread-supply guides to the turret guides, and it has been found that with certain kinds of 35 threads they may become entwined or twisted between the two sets of guides to such an extent as to interfere with the proper operation of the machine.

40 It is the object of the present invention to provide novel and improved thread guiding devices for maintaining the threads between the thread-supply and turret guides in such relation to each other that they will 45 not become entangled or twisted together. To that end the invention comprises the features of construction and combinations of parts hereinafter described and referred to in the claims.

50 The invention will be readily understood from an inspection of the accompanying drawings and the following detailed description of the mechanism illustrated therein.

55 In the drawings, Figure 1 is a side eleva-

tion, partly in section, showing so much of a buttonhole sewing machine as is necessary to illustrate the application of the present invention thereto; Fig. 2 is a detail side elevation of the thread guiding and separating devices; and Fig. 3 is a horizontal view of the same devices.

In the drawings the invention is shown as embodied in the buttonhole sewing machine shown and described in Patent No. 1,063,880 above referred to. In this machine the stitch forming mechanism comprises an upper needle 2, an under needle 4, and a looper 6. The upper needle is eccentrically secured to a reciprocating needle bar 8 which is 60 mounted in a rotary sleeve 10. The under thread mechanism is mounted in a turret 12 which is rotated in unison with the sleeve 10 carrying the upper needle bar during the 65 sewing, the turret and sleeve being given a single revolution during the sewing of each buttonhole, and being rotated rotation after 70 rotation in the same direction in sewing successive buttonholes. The under sewing 75 thread and the stay cord or thread are led to the thread guiding and handling devices on the turret through the hollow link 14 which is carried by the turret and forms a part of the mechanism through which the under thread mechanism is actuated. The 80 lower end of the link is provided with an outwardly flaring sleeve 16 in which the inturned guides 18 for the sewing and stay threads are formed. To avoid the twisting 85 together of the stay and sewing threads by the successive rotations of the turret in the same direction, the threads are supplied through a vertical guide tube 20 which is driven through a sprocket wheel 22 secured to its lower end in a direction opposite to 90 that of the turret, and is given a rotation for each rotation of the turret. The guide tube carries a support 24 for one of the threads, preferably the stay thread, and also 95 carries a guide 26 through which the sewing thread passes. The stay thread is led from the thread supply on the support 24 down through the tube 20, while the sewing thread is led from its supply through the guide 26, which directs the thread from a point in 100 line with the axis of the tube 20 down about the stay thread supply and into the tube 20 below the support 24.

The threads lead through guides located at or near the lower end of the tube 20 to 110

the guides 18 at the lower end of the turret. In accordance with the present invention, the threads are maintained in proper relation by a series of spreaders carried by a shaft arranged between the thread-supply and turret guides and driven in unison with said guides. As shown, the shaft 28 is provided with a series of spreader disks 30, two of which form journals for engaging the bearings 32 and supporting the shaft. The bearings are formed in a bracket 34 which is secured to the under side of the cam support 36, and is constructed to support the shaft in an approximately horizontal position with one end adjacent to the lower end of the link 14, and with the other end adjacent to the lower end of the tube 20. The spreader disks 30 are each provided with thread guides which are preferably arranged on diametrically opposite sides of the shaft. The shaft is driven in unison with the guide tube 20 through a link 38, one end of which is connected by a universal joint with the rear end of the shaft 28, and the other end of which is connected by a universal joint with the driving sprocket 22 for the tube 20. As shown, the lower end of the link 38 is bifurcated to embrace a disk 40, and is pivotally connected with the disk by the diametrically opposite pivot screws 42. The disk 40 is also connected with an arm 44 secured to the end of the shaft 28, and provided with a bifurcated end carrying the diametrically opposite pivot screws 46 for engaging the disk 40. The upper end of the link 38 is bifurcated to embrace a disk 48, and is connected with the disk by the pivot screws 50. The disk 48 is connected with the sprocket 22 by an arm 52, the end of which is bifurcated and is provided with pivot screws 54 engaging the disk. The disks 40 and 48 forming parts of the universal joints are provided with thread guides through which the stay 45 and sewing threads are led from the lower end of the tube 20 to the first spreader disk 30 on the shaft 28. The above construction forms a simple and durable guiding means for preventing the improper contact or entanglement of the threads which is not liable to become defective or inefficient through continued use, and which will not collect and distribute oil upon the threads.

55 While it is preferred to employ the specific construction and arrangement of parts shown and described in embodying the invention in the machine of the patent referred to, it will be understood that this 60 construction and arrangement is not essential to the broader features of the invention, and may be varied and modified as found desirable or best suited to the construction of the machine in which it is to be embodied.

Having explained the nature and object of the invention, and specifically described one form of machine in which it may be embodied, what is claimed is:—

1. A buttonhole sewing machine, having, in combination, stitch forming mechanism, a rotary turret in which the mechanism is mounted, a plurality of thread guides connected to rotate with the turret, a corresponding number of rotary thread-supply guides through which the threads lead to the turret guides, a shaft extending from a point adjacent the supply guides to a point adjacent the turret guides, spreaders on the shaft provided with guides for the threads, and driving connections for rotating the shaft in unison with the thread-supply guides. 70 75 80

2. A buttonhole sewing machine, having, in combination, stitch forming mechanism, a rotary turret in which the mechanism is mounted, a plurality of thread guides connected to rotate with the turret, oppositely rotating thread-supply guides, an approximately horizontal shaft between the thread-supply and turret guides, spreaders on the shaft provided with thread-guides, and driving connections for rotating the shaft in unison with the thread-supply and turret guides. 85 90 95

3. A buttonhole sewing machine, having, in combination, stitch forming mechanism, a rotary turret in which the mechanism is mounted, a plurality of thread guides connected to rotate with the turret, an oppositely rotating guide tube, an approximately horizontal shaft between the guide tube and turret guides, spreaders on the shaft provided with thread guides, a link, a universal joint between the end of the shaft and one end of the link, a universal joint between the other end of the link and the guide tube, and thread guides in the universal joints. 100 105 110

4. A buttonhole sewing machine, having, in combination, stitch forming mechanism, a rotary turret in which the mechanism is mounted, a plurality of thread guides connected to rotate with the rotary turret, thread-supply guides, a shaft between the thread-supply and turret guides, spreader and journal disks on the shaft, thread guides in the spreader and journal disks, and driving connections through which the shaft is driven in unison with the supply and turret guides. 115 120

5. A buttonhole sewing machine, having, in combination, stitch forming mechanism, a rotary turret in which the mechanism is mounted, a plurality of thread guides connected to rotate with the rotary turret, thread-supply guides, a shaft between the thread-supply and turret guides, spreader and journal disks on the shaft, thread guides in the spreader and journal disks, a 125 130

link and universal joints through which the shaft is driven in unison with the supply guides, and thread guides in the universal joints.

5 6. A buttonhole sewing machine, having, in combination, stitch forming mechanism, a rotary turret in which the mechanism is

mounted, a hollow link carried by the turret through which the stitch forming mechanism is actuated, and an outwardly flaring sleeve at the end of the link provided with inturned thread guides for the sewing and stay threads. 15

GEORGE S. HILL.
